UNITED STATES PATENT OFFICE.

JOHN CYGANIEWICZ, OF CHICAGO, ILLINOIS.

DESIGN FOR A HAND BAG.

Application filed January 25, 1923. Serial No. 4,984. Term of patent 14 years.

To all whom it may concern:

Be it known that I, JOHN CYGANIEWICZ, a citizen of the Republic of Poland, residing at Chicago, in the county of Cook and State of Illinois, have invented a new, original, and ornamental Design for a Hand Bag, of which the following is a specification, reference being had to the accompanying drawing, forming part thereof.

The figure is a side elevation of the new and original hand bag.

I claim:

The ornamental design for a hand bag as shown.

JOHN CYGANIEWICZ.
